UNITED STATES PATENT OFFICE.

JOSEPH PAVELKA, OF ST. LOUIS, MISSOURI.

GRINDING-MACHINE.

1,078,949.

Specification of Letters Patent. Patented Nov. 18, 1913.

Application filed May 15, 1913. Serial No. 767,771.

To all whom it may concern:

Be it known that I, JOSEPH PAVELKA, a citizen of the United States, residing at St. Louis, Missouri, have invented a certain new and useful Improvement in Grinding-Machines, of which the following is a full, clear, and exact description, such as will enable others skilled in the art to which it appertains to make and use the same.

10 This invention relates to grinding machines of the type that are provided with a screw conveyer to feed the material through the machine.

One object of my invention is to provide 15 a machine of the character described in which the material that is passed through same will be thoroughly disintegrated.

Another object is to provide a machine 20 of the character described that can be operated more easily than the machines now in general use.

Still another object is to provide a machine of the character described in which the devices that disintegrate the material 25 can be easily and quickly removed from operative position for purposes of cleaning, sharpening or renewal.

Other objects and desirable features will be hereinafter pointed out.

30 Figure 1 of the drawings is a vertical sectional view of a grinding machine constructed in accordance with my invention; Fig. 2 is an enlarged front elevational view partly broken away; and Fig. 3 is a detail 35 sectional view taken on the line 3-3 of Fig. 2.

Briefly stated, my invention consists in a casing that is adapted to contain the material to be ground, a screw-conveyer that 40 conveys said material from the rear end to the front end of said casing, means at the front end of said casing for thoroughly disintegrating said material, and a perforated plate through which the material is discharged from the machine.

Referring to the drawings which illustrate the preferred form of my invention, A designates a casing that is provided with a hopper 1 adjacent the rear end thereof, 50 and B designates a horizontally disposed screw conveyer that is rotatably mounted in said casing. The conveyer B is supported at its rear end by means of a shaft 2 that passes through the rear wall of the casing 55 A and to which may be attached any suitable operating mechanism, not shown, and

at its opposite end by means of a stub-shaft 3 that is journaled in a sleeve 4, said sleeve being in turn supported by a perforated plate 5 that is arranged in the forward end 60 of said casing.

As shown in the drawings, the conveyer B is of smaller diameter throughout than the inside diameter of the casing A so that an opening or slot 6 is formed at the front end 55 of the machine between said conveyer and casing through which the material passes, and an annular shoulder 7 that lies in the same plane as the front face 8 of the conveyer B is formed on said casing for purposes hereinafter appearing.

70 The means herein shown for disintegrating the material that is conveyed to the front end of the machine consists of a plurality of revoluble cutting devices C that 75 are mounted on the front face of the conveyer B and which are arranged between said face and the perforated plate 5, each of said cutting devices comprising a pair 80 of disks 9 and 10 that are secured to a hub 11. The hub 11 is provided with a non-circular bore that co-operates with a correspondingly-shaped extension 12 of a short shaft 13 that is provided on its opposite end with a pinion 14 that is arranged in 85 a recess 15 formed in the front end of the conveyer B. The pinion 14 meshes with a stationary gear-wheel 16 formed integral with the sleeve 4 previously mentioned, and a cover-plate 17 is arranged in the recess 90 15 flush with the face 8 of the conveyer B so as to protect said gears from the material being passed through the machine. By rotating the conveyer B in the direction of the arrow a in Fig. 2, the cutting devices 95 C will be carried in a circular path about the axis of said conveyer, and will also revolve about their own axes because their operating pinions engage the gear 16, which is held stationary by means of the non-circular end 18 of the sleeve 4 that co- 100 operates with a correspondingly-shaped opening in the plate 5. The means for holding the plate 5 in its operative position consists of a lug or projection 19 on same that co- 105 operates with a recess in the casing A, and a cap 20 that is screwed onto the front end of said casing and is provided with a circular flange 21 that engages said plate, as shown clearly in Fig. 2 of the drawings.

110 By referring to the drawings it will be seen that the disks 9 of the cutting devices

C bear against the front face 8 of the conveyer B and the annular shoulder 7 of the casing A, and the disks 10 bear against the perforated plate 5, said disks 10 being preferably concave as shown so that they will be practically self-sharpening. I prefer to provide the pinions 14 with anti-friction devices in order to reduce the labor of operating said pinions, and to this end I provide each of said pinions with a ball-bearing 22 on the inner end thereof to take care of the end thrusts due to the action of the conveyer B, and a ball-bearing 23 at the front end thereof to take care of the side thrusts of said pinions. The conveyer B is also provided at its rear end with a thrust bearing 24, and a hole 25 is provided in the sleeve 4 for lubricating the short shaft 3 that supports the front end of the conveyer B.

In operating my machine, the material to be ground, such, for example, as meat, is placed on the conveyer B through the hopper 1, and said conveyer is then rotated in the direction of the arrow *a* in Fig. 2, thus conveying the meat to the front end of the machine where it passes out through the opening 6 between the inner wall of the casing A and the conveyer B. By referring to Fig. 2 it will be noted that the cutting devices C lie over the opening 6 so that when the conveyer B is rotated, the devices C will be carried around and exert a shearing action on the meat as it is being forced through said opening. The concave disks on the devices C bear against the perforated plate 5 so as to shear the meat a second time before it is discharged from the machine. This shearing action is increased by reason of the fact that the devices C are caused to rotate about their own axes by means of the pinions 14 to which they are connected meshing with the stationary gear 16. It will thus be seen that the meat being forced through the slot 6 is acted on by a constantly changing cutting edge.

To take the machine apart for purposes of cleaning, etc., the cap 20 is unscrewed and removed, when the perforated plate 5 may be drawn out. The cutting devices C being merely slid onto the non-circular end of the shaft 13 may be readily disengaged therefrom, and the conveyer B may be then slid out forwardly. The short shaft 3 will be kept lubricated by the meat fat and juices that enter the hole 25 in the sleeve 4. Because of the fact that the meat is thoroughly disintegrated before being discharged through the perforated plate 5, the operation of the machine will be rendered easy, and the action of the devices C will absolutely prevent the discharge from the machine of any long pieces of uncut tendons or tough gristle.

From the foregoing it will be seen that I

have provided a machine that is very efficient, that on account of the action of the disintegrating devices C and the disposition of suitable anti-friction devices, is easy to operate, is easy to assemble, and by having the operating mechanism for the devices C inclosed, they are protected from foreign matter and injury.

I am aware that minor changes may be made in the construction of my machine without departing from the spirit of my invention.

Having thus described my invention, what I claim as new and desire to secure by Letters Patent is:

1. In a grinding machine, a screw conveyer for forcing the material to be ground from the inlet to the discharge end of said machine, and revoluble cutting disks mounted on the discharge end of said conveyer and having shearing engagement therewith.

2. In a grinding machine, a screw conveyer for feeding material to be ground from the inlet to the discharge end of the machine, and circular disintegrating devices arranged in the discharge end of said machine and having shearing engagement therewith, and which are adapted to revolve about the axis of said conveyer and also about their own axes, the direction of rotation of said conveyer and said disintegrating devices being the same.

3. In a grinding machine, a rotatably mounted member that conveys the material to be ground from the inlet to the discharge end of the machine, and revoluble spool-shaped cutting devices mounted on the discharge end of said member, said cutting devices being so arranged that they will rotate in the same direction as said member.

4. In a grinding machine, a perforated discharge plate, a conveyer for conveying material to said discharge plate, and a plurality of disintegrating devices arranged between the end of said conveyer and said plate, each of said devices comprising a pair of circular knives, one of said knives bearing against the end of said conveyer and the other bearing against said plate.

5. In a grinding machine, a rotatable conveyer provided with a supporting shaft at the discharge end thereof, a gear-wheel loosely mounted on said shaft, a plurality of pinions provided with short shafts that are mounted in the discharge end of said conveyer and that mesh with said gear-wheel, cutting devices that are connected to said short shafts, and a housing that completely covers said gear wheel and pinions.

6. In a grinding machine, a rotatable conveyer provided with a supporting shaft at the discharge end thereof, a gear-wheel loosely mounted on said shaft, means for holding said gear-wheel stationary, a plurality of pinions provided with short shafts

- that are mounted in the discharge end of said conveyer and that mesh with said gear-wheel, cutting devices that are connected to said short shafts, and a housing that completely covers said gear wheel and pinions. 5
7. In a grinding machine, a rotatable conveyer that is provided in its discharge end with a recess, a supporting shaft on said discharge end, a gear-wheel loosely mounted on said shaft and arranged in said recess, a plurality of pinions arranged in said recess that mesh with said gear, and revoluble spool-shaped cutting devices operatively connected to said pinions. 10
- 15 8. In a grinding machine, a rotatable conveyer that is provided in its discharge end with a recess, a supporting shaft on said discharge end, a gear-wheel loosely mounted on said shaft and arranged in said recess, a plurality of pinions arranged in said recess that mesh with said gear, a plurality of cutting devices connected to said pinions, and a cover plate that incloses said gear and pinions in said recess. 20
- 25 9. In a grinding machine, a rotatable conveyer provided with a supporting shaft at the discharge end thereof, a gear-wheel loosely mounted on said shaft, means for holding said gear-wheel stationary, a plurality of pinions provided with short shafts that are mounted in the discharge end of said conveyer and that mesh with said gear-wheel, a plurality of cutting devices connected to said pinions, and anti-friction devices that coöperate with said pinions. 35
10. In a grinding machine, a plurality of revoluble cutters that are arranged in the same vertical plane, each of said cutters comprising a pair of cutting disks, and means for causing said cutters to rotate axially whenever they are revolved about their center of motion. 40
11. In a grinding machine, a rotatable conveyer, a stationary gear-wheel mounted in the discharge end of said conveyer, a plurality of cutting devices arranged in the discharge end of said conveyer that are provided with pinions that mesh with said
- stationary gear-wheel, and a housing that incloses said gear wheel and pinions. 50
12. In a grinding machine, a casing, a conveyer rotatably mounted in said casing in such a manner that a circular space is left between the conveyer and the wall of the casing at the discharge end of the conveyer, and a plurality of revoluble cutting disks that lay over said space and are adapted to travel around said space whenever said conveyer is rotated. 55
13. In a grinding machine, a casing that is provided at its discharge end with a perforated discharge plate, a conveyer arranged in said casing, an annular shoulder formed in said casing in alinement with the discharge end of said conveyer, and a plurality of disintegrating devices that are mounted on the discharge end of said conveyer, each of said devices comprising a substantially flat cutting disk that coöperates with the discharge end of said conveyer and with 60 said shoulder, a concave cutting disk that coöperates with said perforated discharge plate, and a hub portion that unites said disks. 65
14. In a grinding machine, a screw conveyer that is provided at its discharge end with a supporting shaft, a gear wheel mounted on said shaft and having an elongated hub whose end is non-circular, a stationary perforated plate arranged in the 70 discharge end of the machine and having a non-circular opening therein that coöperates with the non-circular end of said hub, and a plurality of revoluble cutting devices that are provided with pinions that mesh with 75 said gear wheel and which are arranged between the discharge end of said conveyer and said perforated plate. 80
- In testimony whereof I hereunto affix my signature in the presence of two witnesses, 85 this twelfth day of May 1913.
